TRAFFIC SIGNAL

Henry J. Smith, Minneapolis, Minn.

Application January 6, 1932, Serial No. 585,016

2 Claims. (Cl. 177—327)

This invention relates to an automatic traffic signal such as now commonly used at the intersection of two or more streets or other thoroughfares to direct traffic. Such signals have commonly been provided with colored illuminated means usually of red or green color, to indicate respectively Stop and Go for the traffic. It has been found in practice that with such signals it is very difficult at times to tell which way the signal stands until the driver is very close to it. In cases of fog and at other times when the sun shines on the signal, the driver often cannot tell which way the signal stands until he is too close upon it to properly control and stop his car.

It is an object of this invention, therefore, to provide an automatic traffic signal having a signal element preferably of the illuminated type which is movable and can thus be seen from a long distance even in foggy and rainy weather, and no matter how the light may shine thereon.

It is a further object of the invention to provide a signal having as a traffic indicating element a rotating arm carrying at one end a signal element such as an illuminated means.

It is still another object of the invention to provide an automatic traffic signal having as a traffic directing element for one street a stationary illuminated means and having as the traffic directing element acting simultaneously for the other street a rotating element preferably comprising lamps disposed at opposite ends of an arm or axis and rotating with said arm or about said axis.

It is also an object of the invention to provide an automatic traffic signal of the self-contained type having motor driven means for changing the signal for the respective thoroughfares and having a clock mechanism for actuating an escapement for determining the periods of actuation.

And a further object is to provide a rotatable "Stop-Go" traffic signal wherein will be incorporated various features and characteristics constituting novel and improved structure both as individual entities of the traffic signal and in combination with each other.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permis-

sible as long as within the spirit of the invention and the scope of the claims which follow.

In the accompanying drawings forming a part of this specification,

Fig. 1 is an elevational view of a traffic signal made according to the invention;

Fig. 2 is an elevational view of a modified type of traffic signal having the features of the invention;

Fig. 3 is a view disclosing a fragment of the traffic signal of Fig. 2, the parts being shown in a different position;

Fig. 4 is an elevational view of a further modified type of traffic signal made according to the invention;

Fig. 5 is an enlarged plan view of the traffic signal of Fig. 1, the hollow steel member and the upright or post being removed;

Fig. 6 is an elevational view of the disclosure of Fig. 5;

Fig. 7 is a detail sectional view taken on line 7—7 in Fig. 6;

Fig. 8 is a detail sectional view taken on line 8—8 in Fig. 7;

Fig. 9 is a detail sectional view of an adjusting tool for the traffic signal;

Fig. 10 is a detail sectional view taken on line 10—10 in Fig. 5;

Fig. 11 is a vertical sectional view detailing features of the disclosure of Fig. 6, a part of the upright or post being shown;

Fig. 12 is a vertical sectional view of the portion of the traffic signal which is above the portion thereof shown in Fig. 11;

Fig. 13 is a detail sectional view taken as on line 13—13 in Fig. 12;

Fig. 14 is a detail sectional view taken as on line 14—14 in Fig. 12;

Fig. 15 is an elevational view of the upper portion or rotary lamps of the traffic signal as seen from the left in Fig. 12;

Fig. 16 is an enlarged vertical sectional view of the clock mechanism of the traffic signal;

Fig. 17 is a horizontal sectional view taken as on line 17—17 in Fig. 16; and

Fig. 18 is a wiring diagram.

With respect to the drawings and numerals of reference thereon, a non-tipable, metallic sub-base for supporting the traffic signal is represented at 20. A base 21 proper of the traffic signal is attached to the sub-base, as by screw bolts 22, the base 21 constituting a portion of a frame in and upon which working parts of the traffic signal are mounted.

An electric motor 23 is suitably supported upon 55

the base 21, and the shaft of the motor 23 carries a worm 24 which meshes with a worm wheel 25 freely rotatable, but fixed against longitudinal movement, upon a vertical shaft 26 suitably mounted in the frame which includes the base 21. Numeral 27 denotes ball-bearings for the vertical shaft 26.

A clutching member 28 is supported by the lower surface of the worm wheel 25, and a complementary clutching member 29 is splined to the vertical shaft 26 at position below the clutching member 28 to be movable longitudinally upon said vertical shaft, toward and away from the worm wheel 25. A retaining nut 30 is supported upon the lower end portion of the vertical shaft 26, and a coil spring 31 about a portion of the clutching member 29 is seated between said retaining nut 30 and said clutching member 29 to urge this clutching member toward the clutching member 28. It will be obvious that when the clutching members 28 and 29 are in engagement and the motor 23 is operating, the vertical shaft 26 will be rotated, the worm 24 driving the worm wheel 25, said worm wheel 25 driving the clutching members 28 and 29, and said clutching member 29 driving said vertical shaft 26. It will also be obvious that when the clutching members 28 and 29 are separated, as shown in Fig. 6, the driving connection between the motor 23 and the vertical shaft 26 will be broken.

The vertical shaft 26 passes upwardly through a top plate 32, and the portion of said vertical shaft directly above the top plate fixedly carries a pinion 33. The pinion 33 meshes with a large gear 34 which is rotatably mounted in the top plate 32, and said gear 34 fixedly carries an upwardly extending, centrally disposed member 35 including undulating cam surfaces 36. An angular member 37 extends upwardly from the center of the member 35. Said angular member 37 removably supports an upright or post 38, as shown more clearly in Figs. 11 and 12, and said post 38 in turn supports the signals of the traffic signal in a manner to be hereinafter fully set forth.

It should be here remarked that the ratio of the pinion 33 to the gear 34 is 1 to 4, so that upon one complete revolution of the worm wheel 25, and with it the pinion 33, said gear 34 makes one-quarter of a revolution. In practice, the arrangement is such that the clutching members 28 and 29 are each time engaged to cause the pinion 33 to make one complete revolution, and upon termination of said complete revolution said clutching members 28 and 29 become disengaged. The traffic signal includes mechanism for causing said clutching members to be again engaged, after each disengagement thereof, upon the termination of an interval of time predetermined by a clock mechanism with escapement.

Of said clock mechanism, which is as disclosed supported upon the base 21, numeral 39 represents a main spring having its outer end anchored at 40 to the frame and its inner end attached, as at 41, to the main shaft 42 of the clock mechanism, said main shaft extending upwardly through the cover 43. Gearing 44 associates the main spring 39 with an escapement 45 in usual manner, and 46 represents the balance wheel of the clock mechanism.

An extension shaft 47 attached to the main shaft 42 is suitably mounted in the top plate 32 and projects upwardly beyond said top plate. A pair of spaced apart, horizontal, interrupted gears, denoted 48 and 49, of insulating material

are mounted upon the extension shaft 47 below the top plate 32 to be freely rotatable upon said extension shaft and slideable longitudinally thereof. The toothless periphery of each of the interrupted gears 48 and 49 carries contact strips, 50 and 51, respectively, and said contact strips, 50 and 51 are in engagement with a conducting strip 52 which is insulatively mounted, as at 53, upon a member 54 fixed to a vertically reciprocable rod 55. The rod 55 is slidably mounted, as at 56, in a bracket attached to the base 21, and in the top plate 32, as at 57, and the upper end of said rod 55 includes an elbow 58 which carries a roller 59 rideable upon the cam surfaces 36. See Figs. 5, 6 and 11. The interrupted gears 48 and 49 with their contact strips 50 and 51, together with the conducting strip 52, the member 54 and the rod 55, constitute a unit of the traffic signal. The member 54 supports a shipper arm 60 having its outer end arranged in a groove 61 which is attached to the lower interrupted gear 49 in such manner that said interrupted gears 48 and 49 will move upwardly and downwardly with the rod 55 as this is moved upwardly and downwardly by travel of the cam surfaces 36 relatively to the roller 59 in a manner to be hereinafter explained.

The contact strips 50 and 51 are adapted to be engaged by a brush 62 carried at the lower end of a conducting spring arm 63. Said conducting spring arm 63 is insulatively attached, as at 64, to a segment 65 which is fixed upon the extension shaft 47 above the top plate 32. A shaped conducting piece 66 is attached to the conducting spring arm 63, as at 67, and the upper end of 35 said conducting piece 66 fixedly carries a hub 68 which is insulatively carried by the upper end of the extension shaft 47. The arrangement is such that when the extension shaft 47 is caused to rotate, the hub 68, the shaped conducting piece 40 66, the segment 65, and the conducting spring arm 63 rotate therewith as a unit to cause the brush 62 to travel over the upper interrupted gear 48 with contact strip 50, or the lower interrupted gear 49 with contact strip 51, as the 45 case may be at a particular time, depending upon whether the roller 59 is upon a high or a low part of the cam surface 36.

The lower clutching member 29 carries a cam finger 69 which is normally engaged by a lever 50 member 70 to separate said clutching member 29 from the clutching member 28, as these parts are shown in Fig. 6. The lever member 70 is pivotally supported upon the frame, as at 71, and includes an integral arm 72 to the outer 55 end of which a coil spring 73 is attached, the opposite end of said coil spring being attached to the frame at 74. Obviously, the coil spring 73 urges an end portion of the lever member 70 toward the cam finger 69. A pin 75 fixed upon 60 the frame limits the extent to which the coil spring 73 can swing the arm 72, and hence limits the distance the lever member 70 can swing in direction toward the cam finger 69. The lever member 70 includes a cut away portion 76 which 65 is shaped as more clearly shown in Fig. 10. Upon rotation of the clutching member 29 in the direction of the arrow in Fig. 5, the cam finger 69 rides against the cut-away portion, from the position as shown in dotted lines to the position 70 as shown in full lines in Fig. 10, to thus be depressed and to in turn depress the lower clutching member 29 against the action of the coil spring 31 to release said clutching member 29 from the clutching member 28. Numeral 77 rep- 75

resents a desirably vertical surface of the lever member 70 at one end of the cut-away portion 76 which is normally engaged by the cam finger 69 to preclude rotation ahead of the lower clutching member 29 beyond the position in which shown in Fig. 5, as will be understood.

Mechanism is provided for precluding rotation of the cam finger 69 and the clutching member 29 in reverse direction when the parts are positioned as in Figs. 5 and 6. Of said mechanism, 10 78 is a post suitably mounted upon the frame, 79 is a lever arm rotatably supported upon said post 78, 80 is a spring for urging said lever arm in a direction toward the lower clutching member 15 29, and 81 is a stop fixed upon said post 78 to limit the inward movement of said lever arm 79. Normally, the lever arm 79 is positioned directly 20 back of the cam finger 69, about as shown in Fig. 5, but is adapted to be swung outwardly, 25 against the action of the coil spring 80, when struck by said cam finger 69 during the later stage of each complete revolution of the clutching member 29 occurring after release of the cam finger 69 from the lever member 70, by 30 mechanism now to be described. Said releasing mechanism includes a solenoid 82 suitably fixed upon the pivoted lever member 70 and having an armature 83. The armature 83 is adapted to move inwardly of the solenoid upon energization 35 thereof, and pivotally supports, as at 84, one end portion of an actuating link 85. The opposite end portion of said actuating link 85 is eccentrically pivoted, as at 86, to an outer portion of a small gear 87. An inner part of said small 40 gear 87 is pivotally attached, as at 88, to said pivoted lever member 70. A coil spring 89, secured to the actuating link 85 and to the lever member 70, normally holds the parts in about the position as shown in Fig. 5. The arrangement 45 is such that upon energization of the solenoid 82 to attract its armature 83, the actuating link 85 is moved in direction to rotate the small gear 87 upon its axis 88 and into engagement with the teeth of the worm wheel 25. Upon engagement of the teeth of the small gear 87 with the teeth of said worm wheel 25, said small gear 87 is caused, by advancement of the teeth of said worm wheel, to complete a revolution, and, 50 evidently, as the wider side of said eccentrically mounted small gear 87 moves to position between the small gear axis 88 and the worm wheel 25, the lever member 70 is swung outwardly upon its axis 71 and against the action of the coil spring 73. The arrangement here is such that said lever member 70 is caused to be swung a sufficient distance to release the stop 77 from the cam finger 69, to thus allow the clutching members 28 and 29 to engage under the action of the coil spring 31. Obviously, upon release of the 55 cam finger 69 by the lever member 70, said clutching member 29 is free to complete a revolution. In practice the cam finger 69 is adapted to engage the stop 77 of the lever member 70 upon the completion of each revolution in the manner as already described and as clearly shown in Figs. 5 and 10.

An insulating ring 90 is suitably secured to the clutching member 29 to rotate therewith, and said insulating ring conveniently supports 70 a contact strip 91 which extends almost the full distance about the insulating ring, but is broken at 92 to provide a dead spot. A brush 93 engages the contact strip 91 and is adapted to lie at the dead spot 92 when the parts are positioned as in Figs. 5 and 6.

Referring to Fig. 18, numerals 94 and 95 represent incoming lead wires, the former being attached to the conducting strip 52, and the latter being attached to the electric motor 23. A lead wire 96 extends between said electric motor 23 and the solenoid 82, and a lead wire 97 extends between said solenoid and a conducting strip 98 insulatively supported upon the top plate 32 as at 99. Said conducting strip 98 is suitably attached to the conducting hub 68. See Figs. 5 10 and 11.

Suppose the parts of the traffic signal as thus far described to be positioned as disclosed in Figs. 5 and 6, with the contact brush 62 out of engagement with either of the contact strips 50 or 51 15 while the clock mechanism is operating step by step, under the influence of the escapement 45, and that eventually said contact brush 62 is rotated to position to engage one of said contact strips 50 or 51. Instantly, the solenoid 82 is energized, the circuit through said solenoid being traced from the incoming wire 94 through the conducting strip 52 and the appropriate contact strip 50 or 51 to the contact brush 62, thence through the elements 63, 66, 68 and 98 and the 20 lead wire 97 to the solenoid 82, and thence through the lead wire 96 and the motor 23 back to the incoming wire 95. Upon energization of the solenoid 82, the armature 83 is attracted to 25 rotate the small gear 87 in the manner as already 30 explained to cause said small gear to engage the teeth of the worm wheel 25. Evidently, the worm wheel 25 is set into operation at the same instant the solenoid 82 is energized, the solenoid circuit and the electric motor circuit being connected in 35 series, and advancement of said worm wheel causes the lever member 70 to be released from the finger 69 in the manner as already set forth, the clutching members 28 and 29, as a consequence, becoming engaged. Thence the electric 40 motor 23 will drive the worm wheel 25 to cause the clutching member 29 to complete one revolution, and the pinion 33 will also, evidently, complete a revolution and rotate the gear 34 and the 45 angular member 37 through one-quarter of a revolution.

The upper end of the vertical shaft 26 fixedly carries a crank arm 100 which pivotally supports a link 101 having an elongated slot 102 arranged in its outer end portion and extending longitudinally of the link. The segment 65 fixedly carries an upstanding pin 103 which is arranged in the elongated slot 102. When the parts are positioned as in Fig. 5, the pin 103 is situated in an inner portion of said elongated slot 102 about as shown, but upon actuation of the clock mechanism under the control of the escapement as hereinbefore set forth, the segment 65 and the pin 103 50 rotate with the shaft extension 47, in the direction of the arrow in Fig. 5, to carry said pin 103 toward the outer end of said elongated slot 102. The crank arm 100 naturally makes a complete 55 revolution each time the pinion 33 revolves through 360°, so that during the earlier stages of actuation of said pinion 33 in the manner as explained, the link 101 is drawn toward the left in Fig. 5 to reset the clock mechanism, it being understood that during each rotating actuation of the traffic signal through an arc of 90° the clock mechanism is wound up precisely the 60 amount it was caused to run down during the immediately preceding period while the traffic signal was in set, stationary position. During the later stages of actuation of the pinion 33, the link 101 is moved back to the position as in Fig. 5. 65

In order to give the signal more accurate timing, it is essential that there be no lost motion in the winding ratchet of the clock mechanism, and this result can be secured by placing said winding ratchet upon the secondary shaft of the escapement. It will be apparent that any other type of self-starting escapement, even an electrical type, can be substituted for the escapement disclosed.

The parts of the traffic signal are shown in Figs. 5 and 6 as when the link 101 has actuated the pin 103 and the brush 62 to the fully wound position of the clock mechanism and has itself moved to position allowing said clock mechanism to operate under the control of the escapement to 10 rotate the extension shaft 47 in the manner as already set forth, to thus cause the brush 62 to rotate in direction to eventually engage one of the contact strips 50 or 51, and the pin 103 to move outwardly in the slot 102. When the brush 15 62 comes into engagement with one of the contact strips 50 or 51, the pin 103 has reached approximately the termination of its travel toward the outer end of the elongated slot 102. Upon said brush 62 coming into contact with one of the contact strips 50 or 51, the electric motor 23 and the solenoid 82 are energized, and the clutching member 29 and the crank arm 100 are caused to travel through a complete revolution, said crank arm 100 actuating the link 101 to reset the extension shaft 47 at the position as shown in Figs. 5 and 6, with the pin 103 and the brush 62, naturally, moved back to their original positions, said brush being out of contact with either of the contact strips 50 or 51.

20 Evidently, the brush 62 will disengage the contact strips 50 and 51 during the period before the clutching member 29 has made a complete revolution. Thus the circuit including the solenoid 82 and the electric motor 23 will be broken and said 25 solenoid will be de-energized. But said electric motor 23 must remain energized to cause said clutching member 29 to complete its revolution which will position the dead spot 92 of the insulating ring 90 adjacent the brush 93. To this 30 end, a lead wire 104 connects the incoming wire 94 with the contact strip 91, and a lead wire 105 connects the brush 93 with the lead wire 96, so that the motor circuit is traced from the incoming wire 94 through the lead wire 104 to the contact strip 91, and thence through the brush 93, the lead wires 105 and 96, and the electric motor 23 back to the incoming wire 95.

Mechanism is provided for maintaining the interrupted gear 48 with contact strip 50, and the 35 interrupted gear 49 with contact strip 51, in stationary position, and for separately adjusting each interrupted gear with contact strip about the extension shaft 47, in order that the contact strips 50 and 51 can be independently set at preferred locations relatively to the initial position 40 of the brush 62. That is to say, it may be desirable to set the traffic signal at "Stop" position upon a street for a longer or a shorter period than said traffic signal is set at "Go" position 45 upon said street. It should be here stated that the cam surfaces 36 include two oppositely disposed high spots and two oppositely disposed low spots, each high spot being arranged at 90° from the adjacent low spots, so that when the roller 50 50 is in engagement with either high spot of the cam surfaces, the contact strip 51 is at the elevation of the brush 62, and when said roller 50 is at either low spot of said cam surfaces, the contact strip 50 is at the elevation of said brush 62. Evidently, the contact strips 50 and 51 are

alternately employed to energize the solenoid 82 and the electric motor 23, one of said contact strips cooperating with the brush 62 to control the interval the signal is set at "Stop" position for a street, and the other of said contact strips 5 50 cooperating with said brush to control the interval said signal is set at "Go" position for said street. Obviously, the contact strip 50 or 51 which cooperates in controlling the "Stop" interval at a street cooperates in controlling the "Go" 10 interval at an intersecting street, and the contact strip 51 or 50 which cooperates in controlling the "Go" interval at a street cooperates in controlling the "Stop" interval at an intersecting street.

The interrupted gear 48 is engaged in its toothed portion by a pinion 106, and the interrupted gear 49 is engaged in its toothed portion by a pinion 107. The pinion 107 is fixed upon a vertical spindle 108 which is suitably mounted upon the frame, and a compression spring 109 20 engages said spindle 108 to steady its action. The pinion 106 is carried by a sleeve 110 which is suitably mounted in the frame and upon the spindle 108, and a compression spring 111 engages said sleeve 110 to steady its action. A tool 112 has 25 one of its end portions constructed to adjustably rotate the spindle 108 independently of the sleeve 110, and its other end portion constructed to rotatably adjust the sleeve 110 independently of the spindle 108. Thus the interrupted gears 30 48 and 49 are not only retained in stationary position after adjustment, but can be independently adjusted to situate the contact strips 50 and 51, respectively, at any desired position relatively to the set position of the brush 62, as will be understood. In Fig. 8 there is disclosed a calibration, denoted 113, which represents "seconds", with respect to which the spindle 108 and the sleeve 110 are independently, rotatably adjustable. That is to say, by reference to the calibration 113, 40 each of the contact strips 50 and 51 can be independently adjusted so that any desired and predetermined period of time, measured in seconds as illustrated, can elapse between the instant when the brush 62 is initially set, as in Figs. 5 45 and 6, and the instant when said brush 62 reaches position to engage the contact strip which is at the particular time at the elevation of the brush.

The traffic signal includes a hollow steel cover member 114 which is attached to the base 21, as 50 by screw bolts 115, providing a housing for the motor 23, the solenoid 82, etc., said cover member 114 including a cylindrical upright 116 which surrounds the upright or post 38 in spaced relation thereto. An upper portion of the upright 55 or post 38 is fixedly attached, as at 117, to a downwardly extending rectilinear frame 118. Said frame 118 includes two oppositely disposed faces each having the word "Go" thereon and two oppositely disposed faces each having the word "Stop" thereon, said faces being arranged 60 90° apart. It will be understood that upon each quarter turn of the angular member 37, the upright or post 38 will be advanced to rotate the rectilinear frame 118 and the "Stop" and "Go" signals 90°.

Also, the upright post 38 suitably and rigidly supports, as at 119, an open-ended casing 120, desirably of metal, the open ends of said casing 120 as disclosed being arranged adjacent the 70 portions of the frame 118 which have "Stop" thereon. A hollow frame 121 within the casing 120 conveniently supports light bulbs 122.

The casing 120 in turn suitably and rigidly supports, as at 123, an open-ended casing 124, de- 75

sirably of metal, the open ends of said casing 124 as disclosed being arranged, facing in the same directions as the open portions of the frame 118 which have "Go" thereon. The casing 124 conveniently supports a horizontal shaft 125 which fixedly carries a member 126 including oppositely disposed arms suitably carrying light bulbs 127 which are adapted to be constantly rotated within said casing 124, numeral 128 representing a small electric motor conveniently supported within the casing 124 for rotating the member 126 with light bulbs 127. The motor shaft has a pinion 129 which meshes with a gear 130 fixed upon the shaft 125. It will be seen from the drawings that owing to the direct drive of arm 126 from motor 128 through gears 129 and 130 and from the respective sizes of said gears that arm 126 is rapidly rotated.

Electric current is supplied to the light bulbs 122 and 127 and to the small electric motor 128 by means of lead wires 131 and 132 which are attached to the incoming wires 94 and 95, respectively, as disclosed. The lead wire 131 is attached to an inner brush 133 insulatively mounted within the cylindrical part 116 of the hollow steel cover member 114, and the lead wire 132 is attached to an outer brush 134 also insulatively mounted within said cylindrical part 116. The brushes 133 and 134 are conveniently supported upon the wall of the part 116. An insulating block 135 is conveniently mounted upon the upright or post 38 and within the cylindrical part 116 to rotate with said upright or post. Said insulating block 135 supports an inner, circular contact member 136 which is engaged by the brush 133, and an outer, concentric contact member 137 which is engaged by the brush 134. Appropriate lead wires extend from the contact members 136 and 137 to the light bulbs 122 and the small motor 128. See Fig. 12. Also, appropriate lead wires extend from said contact members 136 and 137 to a pair of brushes 138 conveniently and insulatively supported within the casing 124, and said brushes 138 carry electric current to the light bulbs 127 through the medium of contact rings 139 suitably disposed upon the member 126 and lead wires extending from said contact rings 139 to said light bulbs 127.

It will be apparent that the casings 120 and 124 will be rotated step by step, along with the upright or post 38 and the "Stop-Go" frame 118 as these are advanced step by step, as set forth, by the driving mechanism of the traffic signal. It will also be apparent that the bulbs 122 and 127 will always be lighted whenever the traffic signal is in operation, and that the small motor 128 will be constantly energized to cause the light bulbs 127 to be continuously rotated. The opposite open ends of the casings 120 and 124 are desirably closed by transparent covers 140. In Fig. 1, 146 represents a green signalling element associated with each cover 140.

In Figs. 2 and 3 a modified type of traffic signal having the features of the invention is disclosed. The signal as there illustrated will be

more appropriately employed to suffice for a single street. The operation of the present signal is substantially the same as the operation of the signal already described, except that the traffic signal of Figs. 2 and 3 is horizontally mounted, 5 as at 141, upon an ordinary street post 142.

In Fig. 4 there is disclosed an overhead cable 143 which supports a housing 144 for working mechanism of the traffic signal, which working mechanism may be substantially the same as already described. A flexible shaft 145 in the present type of signal displaces the post 38 and suspends the signals proper from the housing 144 which is itself suspended from the cable 143. The present signal operates in practice in essentially the same manner as the signal disclosed in Fig. 1 and as already fully described. 15

What I claim is:

1. A traffic signal unit adapted to be disposed at the intersection of two thoroughfares and 20 adapted to direct traffic to go on one thoroughfare and stop on another having in combination, a vertically extending member, means for mounting said member for oscillation through 90 degrees at the end of regular and definite periods, 25 a casing carried by said member having open opposite ends, an arm rotatable about its center in said casing, illuminated means at each end of said arm visible at both ends of said casing, means for constantly rotating said arm and 30 illuminated means without relation to said periods, said rotating arm and illuminated means constituting a go signal for traffic, a second casing adjacent said casing carried by said member having opposite open ends directed at right 35 angles to said ends of said first mentioned casing, illuminated means in said second casing visible at both ends thereof and constituting a stop signal.

2. A traffic signal unit adapted to be disposed 40 at the intersection of two thoroughfares and adapted to direct traffic to go on one thoroughfare and stop on another having in combination, a member, means for mounting said member for oscillation through 90 degrees at the end of 45 regular and definite periods, a go signal unit comprising a casing carried by said member having open opposite ends, an arm rotatable about its center and about a horizontal axis substantially at the center of said casing, a lamp at each 50 end of said arm, means for illuminating said lamps, means for constantly rotating said arm without relation to said periods, transparent means in the ends of said casing so that said rotating lamps are visible at both ends of said 55 casing; a second casing having open opposite ends directed at 90 degrees to said first mentioned ends, lamps in said second casing, means for illuminating said last mentioned lamps, said last mentioned lamps being visible at each end of 60 said second casing and constituting a stop signal whereby said casing with said rotating lamps therein may be alternately directed to said thoroughfares.

HENRY J. SMITH. 65
